[57] ABSTRACT

The alkali metal ferricyanide and alkali metal salt in a bleaching solution for bleaching the silver developed in a color photographic material is regenerated by continually producing a suitable free halogen in a separate vessel and for delivery to the bleaching bath. The quantity of halogen produced is in direct proportion to the need for regenerating halogen as determined by the measurement of the ratio of ferricyanide to ferrocyanide in the bleaching bath. The ratio is measured by means of the redox potential of the bleaching bath which controls the rate of feeding of reactants to the halogen-forming reaction in the vessel.

The free halogen is fed into the bleaching bath under the surface. Other baths for processing the photographic material are regenerated by variably controlling the input of the respective regenerating substances into the respective baths by means of the redox potential.

PROCESS FOR REGENERATING SPENT
PHOTOGRAPHIC SILVER BLEACHING
SOLUTIONS

This invention relates to a process for the regeneration of spent bleaching baths which contain mainly a soluble alkali metal ferricyanide and an alkali metal halide.

Bleaching baths are used in photographic processes for converting the silver formed on development into a salt which is soluble in the fixing bath. The bleaching baths generally used contain an alkali metal ferricyanide, an alkali metal halide and other additives such as buffers to adjust the pH, anti-corrosives, water-softeners and bleaching accelerators.

When these solutions are used for bleaching the silver developed in the color photographic material, the ferricyanide is reduced to ferrocyanide and the halide ions are bound by the oxidized silver as follows:

The efficiency of the bleaching solution therefore diminishes with progressive use so that the exhausted solution must either be discarded or regenerated. It is known that the ferrocyanide can be converted into ferricyanide by the addition of halogens to the exhausted bleaching bath. At the same time, halide ions are formed which compensate for the losses which occur in accordance with equation (I) by the following reaction:

Reoxidation of the ferrocyanide with anhydrous halogens as described e.g. in U.S. Pat. No. 2,515,930, however, has so far not become generally established in practice because the necessary compounds such as chlorine and bromine are very dangerous substances which are difficult to handle.

According to German Patent Specification No 866,909, the bleaching bath is reoxidized by the addition of an alkali metal hypobromite or a mixture of an alkali metal bromate and hydrobromic acid or a mixture of alkali metal bromates and alkali metal bromides with the addition of alkali metal bisulfates, sulfamic acid or sulfuric acid. As is clear from the description and examples, the alkali metal bromate or mixture of alkali metal bromate and alkali metal bromide used in this process is dissolved in the bleaching bath and hydrobromic acid or sulfuric acid is then added. If the mixture which liberates bromine is mixed with acid before addition to the bleaching bath, bromine is liberated spontaneously, which causes serious inconvenience.

The process has the disadvantage that considerable dilution takes place when the reactant which liberates bromine is dissolved in the bleaching bath, with the result that the reaction velocity is very low owing to the low concentrations. The pH of the bleaching bath is greatly reduced by hydrobromic acid or sulfuric acid which has not yet reacted, and although the reoxidation velocity is increased, the decomposition velocity of the bleaching bath is also greatly increased. Quantitative reaction of the reactants added to the bleaching bath

is not achieved within an economical time since the concentrations continue to decrease while the pH rises as the reaction progresses. Repeated adjustment of the pH, which has been suggested for sodium hypobromite, is complicated and time-consuming and results in an undesirable increase in the salt concentrations.

It is an object of this invention to find a simple and economical process for regenerating or reoxidizing spent ferricyanide bleaching solutions. It is important, especially with a view to reducing the ferricyanide concentrations in effluent water, that the bleaching bath should not accumulate unwanted salts such as sulfates in the reoxidation cycle because the whole bleaching bath or large quantities of it would have to be discarded owing to the rapid decrease in activity. It is also desirable to forego adjusting the bleaching bath to very low pH-values because the stability of the bath would thereby be impaired.

This invention relates to a process for the regeneration of spent photographic silver bleaching baths which contain alkali metal ferricyanide and alkali metal halide by reoxidizing the ferrocyanides formed in the process with bromine, characterised in that a quantity of bromine equivalent to the concentration of ferrocyanide at any given moment is continuously produced in aqueous solution in a closed vessel, controlled by the redox potential of the bleaching bath, and flows in under the surface of the bleaching bath. In this way, bromine is only surface of the bleaching bath. In this way, bromine is only produced in small quantities at a time in a closed vessel and therefore cannot escape into the environment.

Numerous reactions are known for producing halogens. They are mainly based on the oxidation of halide ions in acid aqueous solutions, and in some cases compounds of the given halogens in a higher valency state are used as the oxidizing agents. The last mentioned reactions are also known as synproportionating reactions.

Liberation of halogens may be achieved, for example, in accordance with the following reaction equations.

The reactions according to equations (III) to (VIII) are only a selection from the possible oxidation reactions. They have in common the fact that the formation of the halogen is not accompanied by the formation of any reaction products which could reduce the bleaching activity of the bath. The alkali metal salts formed are constituents of the bleaching baths and therefore do not interfere with bleaching even at fairly high concentrations. Since processing of the photographic materials is inevitably accompanied by a certain amount of dilution of the bleaching bath due to liquid being carried into or out of the bath by the photographic material, an equilibrium of salt concentration becomes established. The equilibrium concentration may be so low that further addition of alkali metal halides or alkali metal phosphates to the bleaching bath becomes necessary.

The reactions according to equations (VII) and (VIII) have not achieved any position of importance in general practice since (equation VII) potassium hypobromite must first be prepared by a complicated reaction between bromine and KOH and moreover is an unstable compound and since (equation VIII) iodine used in the bleaching process forms silver iodide which is fixed much more slowly than silver bromide.

Equations (III) to (VI) on the other hand, are suitable for obtaining aqueous bromine solutions in accordance with the present invention. In all cases, the reaction depends on the presence of acid which is used up. If the reaction is fully completed, neutral solutions are obtained if the reactants are mixed in the molar ratios indicated by the equations. According to equations (III) to (VI), bromide ions are oxidised in an acid solution; in equations (III) to (V) bromate is used as oxidising agent and the reaction is therefore a synproportionating reaction.

Reference will now be made to the accompanying drawings in which

FIG. 1 shows a reactor for producing the aqueous bromine solution by the process according to the invention;

FIG. 2 shows a practical example of reoxidation apparatus for the process according to the invention;

FIG. 3 is a schematic representation of the control and dosing pump assembly for the process according to the invention;

FIG. 4 is a diagram representing the dependence of the redox potential on the ratio of ferricyanide to ferrocyanide concentration in a bleaching bath.

Redox potential is an abbreviation for reduction-oxidation potential and is understood hereinafter to mean the electric potential between a platinum electrode dipped into the solution under consideration and a second reference electrode. This second reference electrode is for the purpose of defining the redox potential a so-called standard hydrogen electrode, which is represented by a platinum electrode charged with hydrogen at one atmosphere and dipping into a hydrogen ion solution having a hydrogen ion activity of 1. More convenient are other reference electrodes such as the calomel electrode or the Ag/AgCl electrode. The redox potential is an indication of the oxidising power and therefore indirectly of the concentrations of the oxidized and reduced forms in a redox system.

According to the invention, the starting materials, which are easy to handle in the form of aqueous solutions, are mixed in a small glass apparatus represented

in FIG. 1. In this apparatus, oxidation of the halide ions takes place instantly in acid solution with formation of the free halogen. By using high concentrations of starting materials, such high reaction velocities are usually obtained at room temperature that a high capacity is achieved even with a small apparatus.

Moreover, the volumes required are so small when concentrated solutions are used that in the process according to the invention practically no increase in volume occurs in the processing tank. It is therefore possible to reduce the amount of effluent water by more than 90 percent.

The reactor represented in FIG. 1 substantially comprises two inlet tubes 101 and 102, a reaction chamber 103 and an outlet tube 104. The reaction chamber may be filled with small filling bodies 15 such as Raschig rings, glass spirals or glass pellets. A solution of the acid, for example hydrohalic acid, is introduced through the inlet tube 101 and a solution of oxidising agent through the other inlet tube 102. The two solutions meet at 106 where vigorous mixing occurs. The reaction, which sets in rapidly, takes place mainly in the reaction chamber 103. The length of the flow path of the reactants is considerably increased by the filling bodies 105 and unwanted circulation of the solution due to the thermal flow and the injection effect of the solution entering from 106 are effectively suppressed. After an average time of stay of the solution in the reaction chamber 103 which is equal to the quotient of the volume of the reactor and the quantity passing through it per unit time, the liquid is discharged through the outlet tube 104. According to the invention, the outlet tube 104 is dipped into the spent bleaching bath, and the halogen which is discharged from it in the form of an aqueous solution is greedily taken up by the spent bleaching bath. The ferrocyanide is thereby converted into the required ferricyanide by the reaction represented in equation II and at the same time the halide required for the reaction according to equation I is formed from the halogen.

FIG. 2 shows one embodiment of the reoxidation apparatus according to the invention. It consists of the closed vessel 207 with inlet tube 208 for spent bleaching bath and outlet tube 209 for reoxidized bleaching bath. The reactor (FIG. 1) is fixed inside the sealed vessel 207. The reactor is equipped with non-return valves 210, 211 and 212 which prevent entry of the bleaching bath from the closed vessel 207 into the reaction chamber 203 and prevent escape of free halogen from the reaction chamber 203 into the surroundings by way of the inlet tubes 201 and 202.

A fast stream of spent bleaching bath is directed through the inlet tube 208 to the tip of the glass tube 204 (outlet tube of the reactor) so that aqueous solution of halogen leaving the outlet tube is immediately taken up by the bleaching bath. After a certain time of stay, the bleaching bath passes over the dam 213 which has a safety aperture 237 to the outlet tube 209 from where it can be conducted into the processing tank. Delivery of the bleaching bath may be carried out with the aid of any liquid pump which must, however, be resistant to ferricyanide. The state of oxidation of the bleaching bath is determined whenever required by means of a redox potential measuring chain which may consist, for example, of a platinum electrode 214 as measuring electrode and a silver/silver chloride electrode 215 as reference electrode. Whereas the plati-

num electrode 214 dips directly into the bleaching bath, the silver chloride electrode 215 is placed in a potassium chloride solution 216 inside the inner tube 222 which is surrounded by yet another protective tube 218 filled with potassium chloride solution 217, and electrically connected to the bleaching bath by way of the diaphragms 220 and 221.

The function of the protective tube 218 is to prevent contamination of the silver/silver chloride electrode by bleaching bath entering through diaphragm 220. For this purpose, the tube 218 is filled with potassium chloride solution 216 right up to the storage bulb 219 so that there is a slight flow of potassium chloride 216 from the inner tube 222 into the protective tube 218 due to the hydrostatic pressure on the diaphragm 220. Any bleaching bath penetrating diaphragm 221 to enter the protective tube 218 can be removed through the overflow 223. A small safety aperture 237 in the dam 213 prevents an overdose of free halogen inside the housing 207 in the event of failure of the delivery of bleaching bath. Halogen discharged from the outlet tube 204 after a short time reaches the measuring electrode 214 through the aperture 237, whereby the dosing apparatus 331 (FIG. 3) is switched off immediately. The voltage applied to the electrode leads 224 and 225 is measured by an electric control instrument which forms part of a control and dosing pump assembly.

FIG. 3 is a schematic representation of such an assembly consisting of control instrument 326 and dosing unit 331. The control instrument 326 consists substantially of a direct current amplifier 327 and an mV-measuring instrument 328 with a lower and upper limit voltage contact 329 and 330. Connected to this is a dosing unit 331 which contains a common drive motor 332 for the two dosing pumps 333 and 334. The pumps 333 and 334 are connected at the input end to the storage tank for hydrohalic acid 335 and storage tank for oxidising agent 336 by way of flexible tubes while the pump output ends are connected to the inlet tubes 301 and 302 of the reoxidation apparatus.

In the reactions according to equations (III) to (VII) it is important to keep the ratio in which the starting materials are mixed constant. Pumps with accurately reproducible delivery rates should therefore be used for dosing the solutions. Gear wheel pumps, hose pumps, piston pumps and some types of membrane pumps have been found in practice to be suitable for this purpose. The simplest way of keeping the ratio of delivery rates of the two pumps constant is to use a common drive.

The threshold contact 330 is adjusted to the redox potential which corresponds to the required ratio of potassium ferricyanide concentration to potassium ferrocyanide concentration. The dosing apparatus continues to deliver hydrohalic acid and oxidising agent until the potential on the platinum electrode 214 reaches the adjusted redox potential, and the motor 332 is then switched off at the contact 330. When bleaching developed filmed material, ferricyanide is reduced to ferrocyanide and the redox potential drops. When the redox potential falls below the level to which the contact 330 is adjusted, the motor 332 is switched on again. For the sake of achieving uniform control and hence constancy of operating conditions, it may be advantageous to adjust the delivery rate of the dosing pumps 333 and 334 to the rate of bleaching of the processing machine. The best way to achieve this is to connect the reoxidation

apparatus to the pumping cycle of the bleaching bath tank so that the ferrocyanide concentration of the processing tank is controlled virtually continuously and kept constant. The threshold contact 329 can be used most simply for signalling when the potassium ferrocyanide concentration exceeds a previously adjusted maximum level. Furthermore, a relay may be connected to the threshold contact 329 to act as cable break safety fuse for the lead to the detecting element so that the dosing apparatus 331 will be switched off as soon as the redox potential drops below the value to which contact 329 is adjusted.

FIG. 4 is a diagram showing the relationship between the redox potential and the ratio of potassium ferricyanide concentration to potassium ferrocyanide concentration in a bleaching bath (formulation see example 1). It will be seen that the rate of change of redox potential increases with decreasing proportion of ferrocyanide. In the region of low ferrocyanide concentrations, the control circuit has a high sensitivity to changes in ferrocyanide concentration. Since in practice it is desirable to have only low ferrocyanide concentrations in bleaching baths, the corresponding redox potential range is eminently suitable for controlling a reoxidation system.

The process according to the invention may advantageously be used as a through-flow process for continuously regenerating spent bleaching baths by reoxidation of the ferrocyanide with bromine. Local accumulation of bromine which, as is well known, causes decomposition phenomena, is effectively prevented by the fact that the outlet tube 204 is situated in a region of vigorous flow so that any bromine discharged from it is immediately diluted or used up in oxidizing the ferrocyanide. The redox potential measured by electrometric measuring chains in the bleaching bath can be used not only for controlling the regeneration of the bleaching bath but also for indirectly controlling the regeneration of other processing baths, e.g. a developing, fixing, buffering, hardening or stabilizing bath. This applies particularly to baths in which the active substance is used up at the same rate as the silver is bleached in the bleaching bath, e.g. the color developer bath preceding the bleaching bath. As is well known, the quantity of color developer oxidized in the color developer bath is proportional to the quantity of developable silver halide and hence to the quantity of elementary silver formed. The concentration of color developer substance in this bath decreases accordingly. In the bleaching bath which follows the color developer bath the silver reduces a proportional quantity of potassium ferricyanide. The quantity of regenerating solution required for regenerating the color developer bath is therefore proportional to the quantity of bromine required for regenerating the bleaching bath.

When the redox potential in the bleaching bath sinks, then

- 60 1. the concentration of ferrocyanide in the bleaching bath increases in proportion to the conversion of silver into silver halide, and
- 65 2. the concentration of colour developer in the developer bath decreases in proportion to the formation of dye and image silver.

All that is therefore required is to connect an additional dosing pump for the reactant which regenerates developer to the dosing assembly 331, which pump is

switched on and off simultaneously with the dosing pumps 333 and 334.

The time lag between the bleaching of a certain silver image and the preceding development of the same image results in a corresponding idle time in the control circuit as regards regeneration of the color developer bath. Since, however, the buffering capacity of the developer for color developer substance is relatively high and moreover the average quantity of silver per unit surface area of the photographic material is substantially constant, this idling time does not in practice give rise to any trouble.

In most photographic processing baths the quantity of regenerating solution required for regeneration is proportional to the quantity of photographic material passing through the baths and hence to the total quantity of silver halide whereas in the color developer bath and the following bleaching bath the consumption and regeneration depend only on the quantity of exposed silver halide. It has been found, however, that on an average the quantity of silver halide which has been exposed and can be developed by color development bears an almost constant ratio to the total quantity of silver halide and that this ratio is approximately 1:3. It follows from this that the other processing baths can be regenerated in the same manner, controlled by the electrometric measurement of the redox potential in the silver bleaching bath. This applies particularly to baths in which the concentration of active substance need not be observed strictly accurately, e.g. the final fixing baths, buffering baths, hardening baths and stabilizing baths. For these baths, regeneration controlled by the redox potential in the bleaching bath constitutes a simple and economical method.

EXAMPLE 1

200 metres of a color negative film 35 mm in width which had been exposed imagewise and then color developed were bleached in 10 litres of a ferricyanide bleaching bath of the following composition:

potassium ferricyanide	44 g
potassium ferrocyanide	1 g
potassium bromide	13 g
potassium dihydrogen phosphate	17 g
disodium hydrogen phosphate	7 g
sodium hexametaphosphate	7 g
made up with water to	1000 cc
pH	5.9

Analysis of the bath after bleaching showed that the ferricyanide concentration had dropped to 38.2 g/l and the potassium bromide concentration to 10.7 g/l while the ferrocyanide concentration had risen to 5.3 g/l. The pH of the bath was found to be 5.9. The bath is shown in FIG. 2 for reoxidation of the exhausted bleaching solution. The threshold contact 330 (FIG. 3) was adjusted to a redox potential of 335 mV corresponding to the desired potassium ferrocyanide concentration of 1 g/l as represented in the diagram in FIG. 4. 71 cc of a 5.6 percent potassium bromate solution and 71 cc of a 14.5 percent hydrobromic acid solution were pumped into the inlet tubes 201 and 202, respectively, of the reoxidation apparatus from the dosing apparatus 331 within a few minutes. By that time, the redox potential had increased to 335 mV and delivery of potassium bromate solution and hydrobromic acid stopped. Fresh analysis of the bath showed that the ferricyanide concentration had risen to 42.1 g/l and the potassium bro-

mide concentration to 12.5 g/l while the ferrocyanide concentration had dropped to 0.92 g/l. The pH of the bath remained unchanged at 5.9.

Loss of concentration due to material being carried along with the film passing through the apparatus was made up by the addition of 2 g/l of potassium ferricyanide and 0.5 g/l of potassium bromide.

Photographic tests showed that the bleaching effect of the reoxidised and regenerated bleaching bath was equal to that of the fresh solution.

EXAMPLE 2

10 litres of an exhausted bleaching bath have the same composition as in example 1 were reoxidized and regenerated. 72 ml of a 5.6 percent potassium bromate solution and 72 ml of a solution containing 200 g/l of potassium bromide and 204 g/l of a 36 percent hydrochloric acid were pumped as reoxidation solutions into the inlet tubes 201 and 202 of the reoxidation apparatus (FIG. 2). The redox potential rose to 335 mV and the supply of reoxidation solutions stopped.

Analysis of the bath indicated the presence of 42.0 g/l of potassium ferricyanide, 12.2 g/l of potassium bromide, 0.6 g/l of potassium chloride and 1.0 g/l of potassium ferrocyanide and a pH of 5.9. 2 g/l of potassium ferricyanide and 0.8 g/l of potassium bromide were added to make up the concentration.

The bleaching effect of the reoxidised and regenerated bleaching bath was excellent.

EXAMPLE 3

10 litres of an exhausted bleaching bath of the same composition as in example 1 were reoxidized and regenerated. 72.5 ml of a 5.6 percent potassium bromate solution and 72.5 ml of a solution containing 410 g/l potassium bromide and 230 g/l of an 85 percent orthophosphoric acid were pumped as reoxidation solutions into the inlet tubes 201 and 202 of the reoxidation apparatus according to FIG. 2. The redox potential rose to 335 mV and supply of the solutions stopped.

Analysis indicated 42.1 g/l of potassium ferricyanide, 1.08 g/l of potassium ferrocyanide and 12.94 g/l of potassium bromide. The pH of the bath remained practically unchanged at 5.85. Only 2 g/l of potassium ferricyanide were added to make up the concentration.

The bleaching effect of the reoxidized and regenerated bleaching bath was excellent.

EXAMPLE 4

10 litres of an exhausted bleaching bath having the same composition as in example 1 were reoxidized and regenerated. 24 ml of a 10 percent hydrogen peroxide solution and 16 ml of a 48 percent hydrobromic acid solution were pumped as reoxidation solutions into the inlet tubes 201 and 202 of the reoxidation apparatus according to FIG. 2.

Analysis of the bath indicated 41.8 g/l of potassium ferricyanide, 1.1 g/l of potassium ferrocyanide, 12.4 g/l of potassium bromide and a pH of 5.9. 2 g/l of potassium ferricyanide and 0.6 g/l of potassium bromide were added to make up the concentration. The bleaching effect of the reoxidized and regenerated bleaching bath was excellent.

EXAMPLE 5

180 metres of a color reversal film 35 mm in width which had been exposed imagewise and then developed

were bleached in 10 litres of a ferricyanide bleaching bath of the following composition:

Potassium ferricyanide	100 g
potassium ferrocyanide	1 g
potassium bromide	20 g
disodium hydrogen phosphate	12 g
made up with water to	1000 cc
pH adjusted with acetic acid to	5.2

Analysis of the bath after bleaching showed that the ferricyanide concentration had dropped to 86.9 g/l and the potassium bromide concentration to 15.0 g/l while the ferrocyanide concentration had risen to 12.5 g/l. The pH of the bath was found to be 5.2. The spent bleaching bath was reoxidized and regenerated as in example 1.

The threshold contact 330 was adjusted to a redox potential of 350 mV (redox potential of unused bath). 168 ml of a 5.6 percent potassium bromate solution and 168 ml of a 14.5 percent hydrobromic acid were pumped into the inlet tubes 201 and 202 of the reoxidation apparatus within a few minutes. The redox potential had then risen to 350 mV and the dosing pumps were automatically switched off. Analysis of the bath indicated 95.1 g/l of ferricyanide, 1.3 g/l of ferrocyanide, 18.9 g/l of KBr and a pH of 5.2.

5 g/l of potassium ferricyanide and 1 g/l of potassium bromide were added to make up the concentration. The bleaching effect of the reoxidised and regenerated bleaching bath was excellent.

Although the invention has been described in connection with the potassium ferricyanide bleaching bath, it is to be understood that also other useful bleaching agents such as other iron III complexes of complex-free iron III salts as well as copper II salts can be rejuvenated continuously or batchwise according to the invention provided they are not decomposed by the regenerator solution. In the case of iron III-salts or copper II salts it is advisable to change the pH to lower values in order to avoid hydrolysis and precipitation of the hydroxides.

We claim:

1. A method of regenerating a used photographic silver bleaching bath containing an alkali metal ferricyanide, an alkali metal ferrocyanide and an alkali metal halide, which comprises continually measuring the redox potential of the bleaching bath, thereby sensing the concentration of ferrocyanide formed in the bleaching bath by reduction of ferricyanide simultaneously with the bleaching of silver in the photographic

material, producing a halogen by oxidation of halide ions in an aqueous solution in a closed vessel upon reaction between hydrohalic acid and an oxidizing agent to completely decompose the acid and form the halogen, immediately delivering the free halogen from the closed vessel into the bleaching bath under the surface of the bath, variably controlling the input of the hydrohalic acid and the oxidizing agent into said reaction in the closed vessel in response to the redox potential in

10 the bleaching bath, whereby the quantity of halogen produced in the vessel is equivalent to the concentration of ferrocyanide in the bleaching bath and reacting the halogen with the ferrocyanide to essentially restore the original concentration of ferricyanide and halide in 15 the bleaching bath.

2. A method as in claim 1 wherein the halogen is bromine formed in acid aqueous solution by oxidation of bromide ions.

3. A method as in claim 2 wherein the bromine is formed by reaction of an alkali metal bromate with hydrobromic acid.

4. A method as in claim 2 wherein the bromine is formed by reaction of an alkali metal bromate with an alkali metal bromide and hydrochloric acid.

5. A method as in claim 2 wherein the bromine is formed by reaction of an alkali metal bromate with an alkali metal bromide and orthophosphoric acid.

6. A method as in claim 2 wherein the bromine is formed by reaction of hydrogen peroxide with hydrobromic acid.

7. A method as in claim 1 wherein the bleaching bath is continuously removed from the processing tank, reoxidized while in through-flow and returned to the tank by a pump circulatory system.

8. In the method as in claim 1 wherein the photographic material is treated in one or more additional processing baths, and the concentration of active substances in said additional processing baths is varied essentially in proportion to the quantity of elementary silver converted to a silver salt in said bleaching bath, the improvement according to which the respective additional baths are regenerated by variably controlling the input of the respective regenerating substances into the 40 respective baths in response to the redox potential in the bleaching bath and in proportion to the quantity of halogen produced in the closed vessel and delivered to the bleaching bath.
